UNITED STATES PATENT OFFICE.

EDWARD J. ROWLAND, OF INDIANA, PENNSYLVANIA, ASSIGNOR TO DUGAN GLASS COMPANY, OF INDIANA, PENNSYLVANIA, A CORPORATION OF PENNSYLVANIA.

DESIGN FOR A TOY CANDY-BOX.

45,094.

Specification for Design.

Patented Dec. 30, 1913.

Application filed June 2, 1913. Serial No. 771,319. Term of patent 3½ years.

To all whom it may concern:

Be it known that I, EDWARD J. ROWLAND, a citizen of the United States, residing at Indiana, in the county of Indiana and State of Pennsylvania, have invented a new, original, and ornamental Design for Toy Candy-Boxes, of which the following is a specification, reference being had to the accompanying drawing, forming part thereof.

The figure is a perspective view of a toy candy box showing my new design.

I claim:

The ornamental design for a toy candy box as shown.

EDWARD J. ROWLAND.
